CLAIM

The ornamental design for a 3D scanning optical apparatus for mobile devices, as shown and described.

DESCRIPTION

FIG. 1 is a front-top-left perspective view of a 3D scanning optical apparatus for mobile devices showing our new design;

FIG. 2 is a rear-bottom-left perspective view thereof;

FIG. 3 is a rear-bottom-right view thereof;

FIG. 4 is a front elevational view thereof;

FIG. 5 is a rear elevational view thereof;

FIG. 6 is a left elevational view thereof;

FIG. 7 is a right elevational view thereof;

FIG. 8 is a top plan view thereof;

FIG. 9 is a bottom plan view thereof;

FIG. 10 is a cross-section view taken along line **10-10** in FIG. 7; and,

FIG. 11 is a cross-section view taken along line **11-11** in FIG. 7.

1 Claim, 11 Drawing Sheets
